HANGER FOR APPAREL

John G. Hanson, 306 N. 3rd St., Allentown, Pa.

Filed May 4, 1965, Ser. No. 85,094

Term of patent 14 years

(Cl. D80—8)

The dominant features of my design reside in the portions shown in full lines.

I claim:

The ornamental design for a hanger for apparel, as shown and described.
